CLAIM

The ornamental design for a pair of shoes as shown and described.

DESCRIPTION

The patent or application file contains at least one drawing executed in color. Copies of this patent or patent application publication with color drawing(s) will be provided by the Office upon request and payment of the necessary fee. FIG. 1 is a front and left side perspective view of a first embodiment of a pair of shoes embodying our new design. FIG. 2 is a left side view of the right footed shoe of the pair of shoes thereof.

FIG. 3 is a right side view thereof.

FIG. 4 is a top view thereof.

FIG. 5 is a bottom view thereof.

FIG. 6 is a front and left side perspective view of a second embodiment of a pair of shoes embodying our new design. FIG. 7 is a left side view of the right footed shoe of the pair of shoes thereof.

FIG. 8 is a right side view thereof.

FIG. 9 is a top view thereof; and,

FIG. 10 is a bottom view thereof.

1 Claim, 10 Drawing Sheets
(4 of 10 Drawing Sheet(s) Filed in Color)

Related U.S. Application Data

continuation-in-part of application No. 29/756,340, filed on Oct. 27, 2020, now abandoned.
